UNITED STATES PATENT OFFICE.

GEORGE FRED BLUME, OF RICHMOND, INDIANA.

JOURNAL-BEARING.

1,217,141.

Specification of Letters Patent. Patented Feb. 27, 1917.

Application filed August 25, 1916. Serial No. 116,586.

To all whom it may concern:

Be it known that I, GEORGE F. BLUME, a citizen of the United States, residing at Richmond, in the county of Wayne and 5 State of Indiana, have invented a new and useful Journal-Bearing, of which the following is a specification.

The present invention appertains to journal bearings, and aims to provide a novel 10 and improved journal bearing for railroad cars and coaches, street cars, and other vehicles, it being the primary object of the invention to provide an anti-frictional bearing, which reduces friction to a minimum.

15 It is the object of the invention to provide an anti-frictional journal bearing embodying a novel assemblage of the component elements, whereby the construction is comparatively simple, substantial and inexpensive, as well as being thoroughly practical and efficient, the parts being readily assembled and separated, and the radial and longitudinal strains between the journal and journal box being taken up effectively.

25 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

25 The invention is illustrated in the accompanying drawing, wherein:

Figure 1 is a median vertical section of the structure, portions being shown in elevation.

40 Fig. 2 is an end view of the device, with the journal box lid or cover removed.

Fig. 3 is a cross section taken on the line 3—3 of Fig. 1.

45 Fig. 4 is an enlarged sectional detail illustrating one of the end thrust balls of the anti-frictional rollers, and the manner of assembling the roller, ball and retaining ring.

50 In the drawing, there is designated an axle 1, having each end portion reduced to provide a journal 2 and a shoulder 3 at the basal portion of the journal. A suitable wheel 4 has its hub secured in the usual manner upon the axle 1 adjacent the journal, 55 and the journal is inclosed in a journal box or casing 5, the inner end portion of which

is circular, as at 6, to be surrounded by an offset portion 7 of the wheel 4, to exclude dust and other extraneous matter from the opening 8 in the inner end of the journal box through which the axle 1 extends.

The outer open end of the journal box 5 is of circular formation, and is closed by a journal box lid or cover 9 fitting within said end of the journal box and provided with a peripheral flange 10 overlapping the end of the journal box. As a convenient means for securing the lid to the box, the box is provided with inner longitudinal grooves 11 extending from its outer end and terminating in outturned apertures or sockets 12 at the inner ends of said grooves which extend only a short distance from the outer end of the box, longitudinal bolts 13 being seated in the grooves 11 and having the outturned hooks or lugs 14 fitting in the apertures 12, to prevent the outward movement of the bolts. Said bolts extend through apertures in the flange 10 and have nuts 15 threaded thereon to clamp the lid 80 against the box.

The journal bearing proper is designated 16, and is disposed within the journal box, being provided with a gable-shaped top 17 and slightly inclined upwardly converging 85 sides 18, while the bottom of the bearing 16 is rounded, as at 19. The interior of the journal box is shaped to snugly fit the top and sides of the bearing when the bearing is raised into place within the journal box, 90 whereby to hold the journal box and bearing snugly in place, without vibration, since the journal bearing in moving upwardly within the box, will provide a wedge fit. The bearing 16 is provided at its inner end 95 with a retaining flange 20 projecting upwardly from its top 17 and receivable by a corresponding upper groove 21 with which the journal box is provided in its top adjacent to its inner end. The bearing 16 is 100 further provided with an outstanding flange 22 completely surrounding it and adapted to bear against an outwardly facing shoulder 23 with which the journal box is provided between its ends, and the top 105 of the journal box has a second transverse groove 23' for receiving the upper portion of the flange 23. The bottom of the bearing is normally spaced above the bottom of the journal box, to permit the bearing to 110 move downwardly, or the journal box to move upwardly, whereby the flanges 20 and

22 can be withdrawn from the respective grooves 21 and 23', which will permit the bearing to be withdrawn outwardly from the journal box. Attention is directed to the fact, that when the bearing is moved downwardly within the box, the sides of the bearing being inclined, will be spaced from the side walls of the journal box, whereby the bearing can be withdrawn easily. This also permits the bearing to be readily inserted when moved into place upon the bottom of the journal box, and then when the journal box is moved downwardly or the bearing moved upwardly, the flanges 20 and 22 will be moved into their grooves of the journal box, and at the same time, the bearing will wedge into engagement with the journal box, to provide a tight fit, and to avoid vibrations or rattling. The flange 22 also bears against the shoulder 23 to assist in holding the bearing in place.

The bearing 16 has a longitudinal bore 24 within which the journal 2 projects concentric with and spaced from the walls of said bore, and a set of longitudinal anti-frictional rollers 25 are disposed snugly between the journal and its bearing, whereby to reduce friction, and to take up the radial strains. The rollers 25 are provided with reduced ends or trunnions 26 received by apertures 28 of retaining rings 27 which are disposed at the opposite ends of the rollers to hold them in proper spaced relation. The remote ends of the apertures 28 are reduced, to provide retaining lips 29 for holding anti-frictional thrust balls 30 in said apertures. The trunnions or ends 26 of the rollers are concaved, as at 31, to fit the balls 30, for transmitting the end thrusts from the rollers to said balls and vice versa. The inner set of balls project inwardly from the inner ring 27 and bear against the shoulder 3 to receive the outward thrust of the axle 1, and transfer it to the rollers with the least friction, since the balls 30 can rotate with respect to the axle and rollers. The outer set of rollers project outwardly from the outer ring 27 and bear against an annular abutment or ball race 32 with which the journal box lid 9 is provided, whereby the outward end thrust of the axle is transmitted from the rollers 25 to the journal box lid 9 and journal box 5 by way of the outer set of rollers 30. By the provision of the anti-frictional rollers and balls, friction is reduced to a minimum, and the radial and longitudinal strains are therefore taken up with the least amount of resistance. The balls 30 are free to rotate in various directions, as they are engaged by the rollers 25 during their rotation about their axes as well as the axis of the journal, and said balls therefore reduce the friction.

65 The contacting parts of the journal, roll-

ers, balls, journal bearing and lid can be lubricated in any suitable manner to reduce wear and friction.

The journal box can be provided with any suitable means 33 for attaching it to the frame.

Having thus described the invention, what is claimed as new is:

1. A journal bearing construction embodying a journal box, and a journal bearing therein, said box and bearing having co-operating upwardly converging sides whereby the bearing in its upward movement within the box fits tightly therein. 75

2. A journal bearing construction embodying a journal box, and a journal bearing therein, said box and bearing having co-operating upwardly converging sides whereby the bearing in its upward movement within the box fits tightly therein, said bearing and box having portions adapted to interengage by an upward movement of the bearing in the box to prevent the outward movement of the bearing. 80

3. A journal bearing construction embodying a journal box, having an outwardly facing shoulder near its outer end and an upper groove adjacent to its inner end, and a journal bearing within said box and movable upwardly and downwardly therein, 95 said bearing having an upstanding flange at its inner end to move upwardly into said groove, and having an outstanding flange in its outer end to seat against said shoulder.

4. A journal bearing construction embodying a journal box having an outwardly facing shoulder near its outer end and an upper groove adjacent to its inner end, and a journal bearing within said box and movable upwardly and downwardly therein, 105 said bearing having an upstanding flange at its inner end to move upwardly into said groove, and having an outstanding flange in its outer end to seat against said shoulder, said box and bearing having upwardly 110 converging sides whereby the bearing fits tightly within the box when it is moved upwardly to bring the first mentioned flange into said groove.

5. A journal bearing construction embodying a journal box, a journal bearing in said box, an axle having a reduced journal projecting into said bearing and providing a shoulder, anti-frictional rollers between said journal and bearing and adapted 115 to take up the outward thrust of said axle from said shoulder, and means for transmitting the end thrust from the outer ends of said rollers to the journal box.

6. A journal bearing construction embodying a journal box, a lid attached to the outer end of said box, a bearing within said box, an axle having a reduced journal projecting into said bearing and providing a shoulder, and anti-frictional rollers between 120

said journal and bearing and disposed between said shoulder and lid to take up the outward thrust of the axle.

7. A journal bearing construction embodying a journal box, a bearing therein, an axle having a reduced journal projecting into said bearing and providing a shoulder, anti-frictional rollers between said journal and bearing, rotatable means for transmitting the outward thrust of the axle from said shoulder to the inner ends of the rollers, and means for transmitting the end thrust from the rollers to the journal box including rotatable means coöperating with the outer ends of the rollers.

8. A journal bearing construction embodying a journal box, a lid attached to the outer end thereof, a bearing within the journal box, an axle having a reduced journal projecting into the bearing and providing a shoulder, longitudinal anti-frictional rollers between said journal and bearing, and rotatable thrust members between the ends of the rollers and said shoulder and lid.

9. A journal bearing construction embodying a journal box, a lid attached to the outer end thereof, a bearing within said box, an axle having a journal projecting into said bearing and a shoulder, anti-frictional rollers between said journal and bearing having reduced ends, retaining rings having apertures receiving said reduced ends of the

rollers, and rotatable balls within said apertures of the retaining rings bearing against the reduced ends of the rollers and also bearing against said shoulder and lid respectively. 35

10. A journal bearing construction embodying a journal box, a lid attached to the outer end thereof, a bearing within said box, 40 an axle having a journal projecting into said bearing and a shoulder, anti-frictional rollers between said journal and bearing having reduced ends, retaining rings having apertures receiving said reduced ends of the 45 rollers, and rotatable balls within said apertures of the retaining rings bearing against the reduced ends of the rollers and also bearing against said shoulder and lid respectively, the box and bearing having portions 50 to interengage by the upward movement of the bearing in the box to prevent the outward movement of the bearing, said reduced ends of the rollers being concaved to fit the rotatable balls, and the retaining rings having means for retaining said balls therein. 55

In testimony that I claim the foregoing as my own, I have hereto affixed my signature in the presence of two witnesses:

GEORGE FRED/BLUME.
